ATTORNEY.

UNITED STATES PATENT OFFICE.

EDWARD B. CAMPBELL, OF ST. LOUIS, MISSOURI, ASSIGNOR TO WILLIAMS PATENT CRUSHER AND PULVERIZER CO., OF ST. LOUIS, MISSOURI, A CORPORATION OF MISSOURI.

SIDE-CLOSING PLATE.

1,310,001.

Specification of Letters Patent. Patented July 15, 1919.

Application filed February 10, 1919. Serial No. 276,165.

To all whom it may concern:

Be it known that I, EDWARD B. CAMPBELL, a citizen of the United States, residing at St. Louis, State of Missouri, have invented 5 certain new and useful Improvements in Side-Closing Plates, of which the following is a specification.

This invention relates to certain new and useful improvements in side closing plates 10 for grinders, pulverizers and like machines, the peculiarities of which will be herein-after described and claimed.

The object of my invention is the provision of a two-part plate,—one part securing 15 the other in position,—for closing the side opening in the housing of the mill grinder, or other machine of the class described.

In the accompanying drawing on which like reference letters indicate corresponding parts, Figure 1 represents a side view 20 of a mill of the character described illustrating my improvements; Fig. 2 an end view of the same and partly in section; Fig. 3 a similar side view to Fig. 1 taken 25 on the section plane 2—2 of Fig. 2; and Fig. 4 a detail view showing the preferred form of my closing disk.

The letter A designates the housing of a mill grinder or other like machine, having a 30 rotor shaft B, supported in ball bearings and ring housing (not shown) that are mounted in housing clamps C, each comprising a circular split ring set off from the side of the mill a suitable space D at the 35 top of the ring, and forming part of the side by means of a semicircular shrouding web connection E that extends above the horizontal central plane through the shaft as shown in Fig. 3. The object of this form 40 of mounting the bearings, is to provide the space between each side of the mill and the adjacent bearing, as required by insurance ruling. A bolt F at the top of the clamping ring, serves to tighten the clamp 45 upon the ring housing of the ball bearing when inserted in the clamp. In Fig. 1 the ball bearing and its ring housing are not shown, in order to show clearly the location of my improvements. In each side 50 of the mill is a circular opening G, substantially the size of the opening in the said clamping ring C, in order to allow of passing the shaft and rotor within the mill through the clamp and side of the mill. 55 In order to close this opening G I provide

a thin flat plate made in two parts, H and I. The divided closing plate is preferably circular, and the dividing line preferably is located through the center of said disk, corresponding to the horizontal central plane 60 through the shaft or otherwise. A circular opening J is formed when the disks come together in proper position on the outside of the mill to embrace the shaft B. In the clamp housing web connecting the lower 65 part of the clamp to the side of the mill, is formed a groove K, preferably continuous as indicated in Fig. 3, and close to the outside of the mill. In this groove fits the lower half H of my improved disk. The 70 groove being struck in an arc from the center of the shaft, corresponds with the circular half disk H, so that when the shaft is in position the lower half disk can be placed upon the shaft and then rotated 75 around the shaft to its position in the said groove K. The groove thus supports the disk which can only be removed by rotating it to an upper position again. It is necessary to rotate one part of the plate 80 into its closing position, because the said plate is semi-circular, corresponding to the lower part of the bearing housing as shown in Fig. 3. The shaft with its attachments must first be mounted in the casing and the 85 bearings must be clamped in their housings. The divided closing plate is the last to go into place, and under these circumstances and because of the construction shown, one part at least of the divided closing plate 90 must be rotatably mounted in said groove in order to adjust it to its closing position. The upper half-disk I then slips into position upon the shaft, with the parting line 95 at the bottom meeting the corresponding line or edge of the lower disk, and with the bottom ends at the outside located in the corresponding ends of the groove above the parting line of the disk, as shown in Fig. 3. This divided closing plate lies outside 100 of the casing and so does the groove K which is practically in the plane of, or flush with, the outer face of the casing, and the said plate therefore lies partly in said groove and partly out of the groove when fully adjusted to its closing position. The upper ends of said groove therefore hold the lower ends of the upper disk, and some means for holding the top of the disk I 105 against the side of the mill, and against 110

rotation about the shaft, is required. I have shown such means in the form of two extensions or lugs L, having holes through which pass screw bolts M into the side housing of the mill. These lugs project out far enough from the disk I, to allow the ready insertion of the screw bolts without interference from the clamping ring C, as shown in Fig. 1. In Fig. 2 it will be observed that the space D between the clamp and the side of the mill is too small to allow the ready insertion of the screw bolt M; and other fastening facilities, such as the lugs M, are required. Other means however may be employed to secure the upper-half-disk I in position, and thus maintain the located position of the half-disk H. While this closing plate is divided horizontally through the center it may be otherwise divided, as long as one part, at least, is rotated adjustably in the groove K in

the connecting web between the casing side and the bearing housing that is offset by said web from the side of the casing.

I claim:

The combination with a mill shaft and a casing having an offset bearing housing connected by a semi-circular web to said casing,—said casing having an opening in its side opposite said offset housing and 30 said web having a groove concentric with said opening and substantially in the plane of the outside face of the casing,—of a circular divided closing plate fitting against the face of said casing and rotatably located 35 partly within said web groove and partly outside of said groove, and means to secure said closing plate in its rotated closing position.

In testimony whereof I have affixed my 40 signature.

EDWARD B. CAMPBELL.
